ASSEMBLY FOR SUPPORTING REFRIGERANT CONTAINERS IN REFRIGERATOR CARS

Alfred L. Thompson, Munster, Ind., assignor to Standard Railway Equipment Manufacturing Company, Chicago, Ill., a corporation of Delaware

Application April 12, 1947, Serial No. 741,101

4 Claims. (Cl. 62—17)

1

This invention relates to railway refrigerator cars of the general type shown in Patent 2,136,999 granted to Charles D. Bonsall on November 15, 1938, and known as top bunker refrigerator car.

One of the objects of the invention is to provide a refrigerant container which extends uninterruptedly between the opposite ends of the car and eliminate the spaces between the several bunkers shown in Bonsall's Figure 2, thus materially increasing the ice capacity of the refrigerant container without occupying any more space in the car, i. e., without encroaching upon the lading space of the car.

Another object of the invention is to join the container, supporting beams and drip catcher into a unit assembly and to hinge such assembly to a wall of the car and to provide means to engage and disengage such assembly to or from the roof of the car adjacent the longitudinal center thereof.

Another object is to provide inside carlines extending crosswise of the car below and adjacent the roof of the car to partially support such assembly independently of the roof carlines or roof structure of the car.

In the drawing the figure shows a transverse section of part of a railway refrigerator car having my invention applied thereto.

The drawing shows the usual parts of a railway refrigerator car, such as side wall 2; side wall flue 3; roof structure 4 including roof carline 5; hatch opening 6 and hatch frame 7.

The refrigerant container 10 is positioned below the hatch opening 6 filling the container. A plurality of beams 11 are positioned below the container 10 and secured thereto by bolts 8 for supporting the container. The drip catcher 12 is supported by the beams 11 and is spaced from the container (and secured thereto by the bolts 9) to form a duct 13 therebetween, which duct 13 communicates with the flue 3 at one end thereof and with the interior of the car 14 (at 15) at the other end thereof.

The container assembly 10, 11, 12, and 13 (preferably through the medium of the beams 11) is hinged at 16 to the side wall 2 of the car so that the assembly may be swung downwardly, against the side wall of the car for inspection, cleaning and repair if necessary.

In the preferred form I support the inner side of the assembly independently of the roof of the car, therefore, I provide inside carlines 18 which extend between and are secured to and supported by the opposite side walls of the car. These in-

2

side carlines 18 are independent of the roof carlines 5 and, in fact, of the roof structure so in event of a failure of an inside carline the roof would not be affected; in other words, it would not leak. The brackets 19 are secured to the inside carlines 18 and the bolts 20 pass through the inner ends of the beams 11 and the brackets 19. Thus I have provided removable means for engagement and disengagement of the assembly to or from the roof.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. A refrigerant container assembly for a railway refrigerator car having a wall, a vertical flue forming a part of said wall, a roof and a hatch opening in said roof, said assembly comprising a refrigerant container below said hatch opening, beams extending across the bottom and one side of said container and secured thereto, said beams being removably secured to said roof, a drip catcher supported by said beams and spaced from said container to form ducts between said beams which communicate with said flue at one end thereof and with the interior of the car at the other end thereof, and a hinge swingably supporting one side of said assembly to said wall, so that upon removal of removable means said assembly may be swung downwardly from said roof.
2. A refrigerant container assembly for a railway refrigerator car having spaced side walls, a vertical flue forming a part of one of said walls, a roof, a hatch opening in said roof and an inside carline extending between said walls, said assembly comprising a refrigerant container below said hatch opening, beams positioned below and secured to said container which extend crosswise of the car, a drip catcher supported by said beams and spaced from said container to form ducts between said beams which communicate with said flue at one end thereof and with the interior of the car at the other end thereof, a hinge swingably supporting one side of said assembly to one of said walls, and removable means for engagement and disengagement of said assembly from said inside carline.
3. A structure as defined in claim 1 wherein said container and drip catcher extend uninterruptedly between the opposite ends of the car.
4. A refrigerant container assembly for a rail-

way refrigerator car having a roof and a wall, said assembly comprising an elongated refrigerant container, a beam extending across the bottom and one side of said container and secured along one of its edges to said container, a drip catcher extending across the bottom and one side of said container in spaced relation thereto and secured to the other edge of said beam, forming ducts between the container and drip catcher, a hinge at one end of said beam for hinging said structure to a wall of a refrigerator car, and removable means at the other end of said beam for removably securing said structure to the roof of a refrigerator car.
